UNITED STATES PATENT OFFICE

93,128

DESIGN FOR A TOASTER

William A. Pentecost, Oakland, Calif., assignor to
Ace Mfg. Co., Emeryville, Calif., a corporation
of California

Application May 24, 1934, Serial No. 51,902

Term of patent 7 years

To all whom it may concern:

Be it known that I, WILLIAM A. PENTECOST, a citizen of the United States, and a resident of Oakland, in the county of Alameda and State of California, have invented a new, original, and ornamental Design for a Toaster, of which the following is a specification, reference being had to the accompanying drawing, forming part thereof, wherein

Figure 1 is a perspective view of a toaster embodying my new design, and arranged for its use.

Figures 2 and 3 are respectively side and end elevations of the structure shown in Figure 1, but with adit and exit doors of the toaster closed.

The surface shading is intended to represent generally the use of contrasting colors, or degrees of color, for the different exterior parts of the structure.

I claim:—

The ornamental design for a toaster, substantially as shown and described.

WILLIAM A. PENTECOST.
